UNITED STATES PATENT OFFICE.

LEWIS D. RAYNER, OF DAYTON, ASSIGNOR TO CHRISTOPHER EMRICH, OF COLUMBUS, OHIO.

DESIGN FOR A HEATING-STOVE.

SPECIFICATION forming part of Design No. 22,952, dated December 5, 1893.

Application filed October 24, 1893. Serial No. 489,052. Term of patent 7 years.

To all whom it may concern:

Be it known that I, LEWIS D. RAYNER, a citizen of the United States, residing at Dayton, in the county of Montgomery and State of Ohio, have invented and produced a new and original Design for Stoves; and I do hereby declare the following to be a full, clear, and exact description of the same, reference being had to the accompanying drawing, forming a part thereof.

My design is intended for heating stoves; and its essential or leading features consist of substantially the ornamentation for the dome, body, fire-pot, the frame surrounding the fire-pot, and base of this class of stoves represented in the drawing referred to, in which—

A represents the dome having a series of circular scrolls forming rings A' at regular intervals. Below these are a plain ring B and an ornamental border B' composed chiefly of spiral scroll work. At the base of this latter is a nearly plain projecting ring C, the ornamentation of which consists of light scroll work placed at considerable intervals apart. The body D of the stove is of cylindrical form

and is furnished with two doors E E'. The ornamentation of these doors consists of a single unit formed of scroll figures branching in various directions from a common place of origin. Below these doors is a nearly plain ring F somewhat similar to the ring C having ornamental scrolls corresponding in position but inverse in direction to those of the ring C. Pendent to the ring C by means of the ornamental brackets G is an ornamented ring G' which is widened and curved upward at the front of the stove. Under this ring is the fluted fire-pot H resting on an expanded base I also ornamented with spiral scrolls extending into the legs which support the whole structure.

What I claim is—

The design for a stove as herein shown and described. 45

In testimony whereof I affix my signature in presence of two witnesses.

LEWIS D. RAYNER.
